ROCKING SLIDE

William H. Noelting, Evansville, Ind., assignor to
 Faultless Caster Company, Evansville, Ind., a
 corporation

Application March 21, 1932. Serial No. 600,108

8 Claims. (Cl. 16—42)

This invention relates to a rocking cushion slide.

Heretofore in the slide industry, slides have been produced which have a stem or center anchoring member that is rigidly associated with the slide body and said slide body has been of suitable formation such as an integral cast construction or of multiple sheet metal construction, or of a molded construction reenforced with metal.

Likewise, so-called rocking stem slides have been used in the industry and these may be of molded or cast base construction, providing a central chamber or a sheet metal base construction providing a central chamber and mounted in the central chamber is a headed anchoring member whereby the slide is anchored to a furniture leg or the like.

Slides also have been used in the industry wherein a cushion member has been interposed between the slide base and the end of the furniture leg.

Each of the aforesaid types of construction, by reason thereof, has inherent disadvantages of lack of strength, of being noisy, inability to rock or inability to be driven into an anchoring connection with the leg to be supported thereby.

The present invention includes all of the advantages of these slides, to wit, it can be driven for anchorage to a furniture leg, it is cushioned for contact between the leg and the slide body, and may be cushioned within the central chamber for eliminating the noise incident to the connection between the anchoring member and the slide body and has sufficient strength that it will not break when in use. In other words, it will have a relatively long life.

The full nature of the invention will be understood from the accompanying drawing and the following description and claims:

In the drawing, Fig. 1 is a central sectional view of one form of the invention.

Fig. 2 is a similar view of a modified form thereof, the anchorage between the top and the bottom of the base or slide body being different from that shown in Fig. 1.

Fig. 3 is a view of a slide similar to Fig. 2 but wherein the metal base is inclosed by a molded construction that is non-shatterable, such as hard rubber.

Fig. 4 is a view similar to Fig. 3, except that the molded material is of vitreous character or semi-shatterable and the form of the metal base is different from the preceding forms of the base.

Fig. 5 is a view similar to Fig. 1 and of a slightly

modified form of top and interior cushion arrangement.

Fig. 6 is a view similar to Fig. 1 and of a slightly modified top and interior cushion construction.

Fig. 7 is a view similar to Fig. 1 and of a slightly modified form of top and base connection.

Fig. 8 is a view similar to Fig. 1 and includes an additional base member.

Fig. 9 is a view similar to Fig. 8 but the auxiliary base is of slightly different form.

Fig. 10 is a view similar to Fig. 1 but of a slightly different form of top and base connection.

Fig. 11 is a view similar to Fig. 1 but of a different type of top and base connection.

Fig. 12 is a view similar to Fig. 1 and differs from Fig. 10 in the formation of the top.

Fig. 13 is a view similar to Fig. 12 but of a reverse form of top construction.

Fig. 14 is a view similar to Fig. 10 but of a slightly modified form of base construction.

Fig. 15 is a view similar to Fig. 2 but of a slightly modified form of top construction.

Fig. 16 is an elevational view of a drive-screw type anchorage and of a modified form of head enlargement.

In the drawing similar numerals indicate like or similar parts. For example, numbers of the one hundred series refer to parts shown in Fig. 1 and similar numbers of the two hundred series refer to similar or like parts in Fig. 2, and so on for the several figures. For example, the nail body in Fig. 1 is indicated by the numeral 110 and the nail body in Fig. 15 is indicated by the numeral 1510. All parts are numbered in all of the figures in this manner and to reduce the specific description, only the respective departures in each figure will be mentioned hereinafter, it being understood that the numerals on the drawing indicating parts not mentioned, refer to like parts and for like purposes.

In Fig. 1 of the drawing, 110 indicates an upstanding anchoring member which herein is shown as of the nail type, although a so-called driving screw might be substituted therefor. The nail 110 terminates in an enlargement or head 111 which has a rounded peripheral edge 112 and a flat top 113. The purpose of this flat top is that it will engage the relatively flat interior surface 114 of the base member 115 and in the driving of the slide on to the furniture leg, the spike portion 110 will be specifically perpendicular to the plane of the base of the slide, thereby insuring correct driving and anchorage of the slide.

The base of the slide has an upwardly and inwardly directed peripheral portion 116 which

in Fig. 1 is turned inwardly as at 117 to engage or overhang the portion 118 of a top plate 119. The top plate 119 is centrally apertured as at 120 and the upstanding member 110 extends through the aperture and may rock therein without interference from the wall of the aperture. Mounted on the top plate and as shown in Fig. 1, partially nested within the portion 117 is a cushion member 121 that is apertured as at 122 and the upstanding portion 110 extends through the aperture 122. The cushion 121 is adapted to engage the end of the furniture leg.

This cushion 121 also has another function, to wit, when the slide is to be driven on to the leg, the top 113 thereof engages the surface 114 and impact or a hammer blow on the exterior of the base 115 serves to drive the nail or spike into the furniture leg. If this driving movement is continued to the proper degree, the cushion 121 will be partially compressed. After the force of impact or driving force is removed, the cushion 121 reexpands and tends to push the slide away from the furniture leg. This tends to force the top plate downwardly along the upstanding member 110 until the enlargement 111 or head engages the bottom side of the top plate 119 adjacent the opening 120. Enlargement 111 is of greater area than the opening 120.

Herein the top plate 119 having the base engageable interlocking portion 118 is extended downwardly as at 123 and this forms cup in which, if desired, may be mounted a cushion member 124 having the central aperture 125 therein.

35 In the initial manufacture of the slide, the cushion member 124 is considerably expanded and is nested in the inverted cup formed by the top plate and the portion 123 extending therefrom. When the top plate and the base plate are associated together, the two are forced together in nested relation, thereby compressing the cushion member 124 and putting the same under constraint. The top plate is then turned inwardly into interlocking relation, as shown at 40 117, the latter portion engaging portion 118 and locking the construction together. Thereafter the cushion member 121 is mounted on the slide and the latter serves the two purposes before mentioned.

50 In Fig. 2 like or similar parts are indicated by similar numerals of the two hundred series. Specifically this form of the invention differs from the form shown in Fig. 1 in that the base plate 215, which includes the upwardly peripheral portion 216, is offset inwardly as at 227 for obtaining a greater mechanical locking than is obtained by the portion 217. This annular inwardly offsetting also reinforces the base of the slide.

66 In both forms of the invention and in all subsequent forms, it will be observed that the normal action of the slide is such that the head 111 preferably does not contact the base but must contact the base for the driving of the slide on to the furniture leg. Likewise in both forms of this invention and in the remaining forms wherein the slide enclosed cushion member is employed, the retention of such cushion member in the slide and under compression insures greater resistance to the tilting action. In other words, when the tilting force is removed, this cushion member tends to immediately realign the respective parts so that the slide and its anchorage will maintain the perpendicular relation shown in Fig. 1.

80 In Fig. 3 there is illustrated a modified form of the invention, wherein all of the advantages of the metallic slide, so far as strength is concerned, is retained or embodied therein and a non-metallic sliding surface is provided. In this form of the invention, there is molded upon the metallic base 315 an outer base 330 which by reason of the portion 331 is retained on the metal base slide structure. This molded base structure is of a non-shatterable material, such as relatively hard rubber of any desired color. In other words, the base 330 may be hammered for driving on the slide without the danger of shattering. In other words, this form of the invention is identical with that shown in Fig. 1 with the addition of the external auxiliary molded base.

85 In Fig. 4 there is illustrated a modified form of the invention which differs from the form shown in Fig. 3 in that it is arranged to be of a vitreous or shatterable molded material, such as glass or of shatterable phenol condensation type. In this form of the invention, the auxiliary base 430 includes a central aperture. The slide is attached to the furniture by inserting a tool in the aperture 432 to engage the base 415 and then the slide is driven on as before set forth. In this form of the invention also, the metal base 415 instead of having a side wall 416 arcuate in radial section, has an upstanding substantially vertical 100 cross section and terminates in an inturned flange 417.

90 In Fig. 5 there is illustrated a modified form of the invention and this form differs from that shown in Fig. 1 in that the top plate 519 has a 110 downwardly directed peripheral wall 523 that terminates short of engaging the base. The cushion insert 524 in this form of the invention, is shown provided with a projecting flange 529. The other parts of the slide are substantially similar to that 115 shown in Fig. 1.

95 Fig. 6 illustrates a modified form of the invention which only differs from Fig. 1 in that the top 619 has a downwardly and inwardly directed peripheral skirt 623 which, in this instance, similar to Fig. 1, also engages the base 625.

100 In Fig. 7 a modified form of the invention is illustrated, wherein the depending side wall of the top plate is closely associated with the upstanding outer side wall of the base, and in this respect the invention is similar to that illustrated in Fig. 4. In this form of the invention also, there is an offsetting but instead of being in the outer base forming member, the same is provided in the top and in this respect it is a reversal of 120 the form shown in Fig. 2. In Fig. 7, the top plate 719 includes an upwardly directed annular flange portion 727 and a curved portion 718 that is gripped by the upper edge 717 of the outwardly and upwardly curved side wall 716 of the base 715. The top plate has a depending skirt 723 that is positioned immediately adjacent and in engagement with portion 716.

125 Fig. 8 illustrates a form of the invention where in the base plate 815 has an upwardly directed side wall 816 and an inwardly locking portion 817 similar to that shown in 1. The top plate 819 has a curved portion 818 that terminates at 823. Superimposed upon the base plate is an auxiliary base plate 835 with an upstanding peripheral portion 834 that terminates in an edge 833 which abuts the edge 823. Both top plate and auxiliary base plate are retained in chamber forming relation by the outer base plate.

130 In Fig. 9 there is illustrated a form of the in-

vention which is substantially a duplicate of that shown in Fig. 8, except that the auxiliary base plate 935 is centrally apertured as at 932, so that for driving purposes the head of the anchoring member may directly engage the base 915 and in all other respects this form of the invention is similar to that shown in Fig. 8.

In Fig. 10 there is illustrated a form of the invention that is somewhat similar to Fig. 7, except that the top plate is not corrugated. In other words, the form of the invention shown in Fig. 10 differs from that shown in Fig. 1 by the depending side wall 1023 of the top plate 1019 closely engaging the curved outer wall 1016 of the base 1015, the parts being locked together as at 1017.

Fig. 11 is substantially similar to Fig. 10, except that instead of the depending wall carried by the top plate thereof, terminating adjacent the bottom or flat portion of the base, the depending portion terminates intermediate the plane of the base and the top plate and in this respect, is similar to the forms of the invention shown in Figs. 5, 8 and 9, except that like Figs. 8 and 9, the top plate in the present form closely engages the side wall portion 1116 of the base member 1115. The top plate 1119 having its portion 1118 and depending wall 1123 is locked in slide forming relation by the edge 1117 of the base member 1115.

Fig. 12 is similar to Fig. 10 in all respects, except the top plate 1219 adjacent the aperture 1220 is extended upwardly in collar formation as at 1236.

In Fig. 13, the structure illustrated is the same as that shown in Figs. 10 and 12, except that the top plate 1319 has its central aperture 1320 defined by a downwardly directed extension or collar 1336.

In Fig. 14 there is illustrated a modification substantially similar to that shown in Fig. 10, except that the locking portion of the base 1417 includes an upstanding collar 1437, and the same forms an annular groove to receive the outer cushion member 1421. In this respect Fig. 14 illustrates a form of the invention somewhat similar to the form shown in Fig. 7, except that the recess for the outer cushion member, in this instance, is formed by the base member and not by the top member, as in Fig. 7.

In Fig. 15 a modified form of the invention is illustrated, wherein the base member is substantially identical to that shown in Fig. 1. The top plate 1519, however, is provided with the depending portion 1518 and thence with an outwardly directed, curved outline in radial section, extension 1523 which terminates in an inturned portion 1540 that bears upon the base 1515. The base 1515 includes the side 1516 and the locking portion 1517.

It will, of course, be understood that the top plate in any one of the figures, except Fig. 12, may be provided with a downwardly directed collar indicated, by the numeral n plus 36, where n , is the number of the figure multiplied by one hundred. Also any one of the top plates except that shown in Fig. 13, may have an upwardly directed collar defining the aperture and said collar would bear the same numeral.

It will also be apparent that in those forms of the invention wherein the auxiliary base may be employed.

The various forms of anchoring the base and top plate together may be readily interchanged in the various forms of the invention.

It is also to be noted that while the preferred

form of the invention illustrates in each instance a head structure for the anchoring member wherein there is provided a curved side wall that terminates in a flat head, a frusto conical head may be substituted, see Fig. 16, or a partially spherical head may be substituted therefor. The frusto conical head would be preferred to the rounded head, because of the so-called self centering action obtained in driving.

While the anchoring member is shown as a nail, as before mentioned, it may be of driving screw formation, see Fig. 16, or it may be of standard detachable caster pintle form.

The invention claimed is:—

1. A rocking slide construction comprising an outer metal base having an upstanding anchoring portion, a centrally apertured metal top plate having a base interlocking portion, said base and plate having an interlocking connection and forming a chamber, a headed anchoring member, the stem portion thereof being of less area than the plate aperture permitting relative rocking and axial movement therebetween, the headed portion being positioned in the chamber, resilient means carried by the top plate and through which the anchoring member extends, said means permitting head and base operative contact for slide mounting and normally separating the same when mounted, and a cushion member included within the chamber and having opposite faces engaging the plate and base and including a tubular aperture extending axially therethrough, and of less cross-sectional area than the area of the anchoring member head.

2. A rocking slide construction comprising an outer metal base having an upstanding anchoring portion, a centrally apertured metal top plate having a base interlocking portion, said base and plate having an interlocking connection and forming a chamber, a headed anchoring member, the stem portion thereof being of less area than the plate aperture permitting relative rocking and axial movement therebetween, the headed portion being positioned in the chamber, resilient means carried by the top plate and through which the anchoring member extends, said means permitting head and base operative contact for slide mounting and normally separating the same when mounted, and an outer molded base substantially enveloping the metal base, the shape of the latter being such that when molded into the outer base the two parts are permanently locked together, said molded base including an exposed aperture in alignment with the plate aperture, said base aperture extending to the metal base for exposing same for slide drive mounting.

3. A rocking slide construction comprising an outer metal base having an upstanding anchoring portion, a centrally apertured metal top plate having a base interlocking portion, said base and plate having an interlocking connection and forming a chamber, a headed anchoring member, the stem portion thereof being of less area than the plate aperture permitting relative rocking and axial movement therebetween, the headed portion being positioned in the chamber, resilient means carried by the top plate and through which the anchoring member extends, said means permitting head and base operative contact for slide mounting and normally separating the same when mounted, and an outer molded base substantially enveloping the metal base, the shape of the latter being such that when molded into the outer base the two parts are permanently locked together, said molded base including an exposed aperture in alignment with the plate aperture, said base aperture extending to the metal base for exposing same for slide drive mounting.

locked together, said outer base being of shatterable material and including an aperture in alignment with the plate aperture, said base aperture extending from its lower surface to the metal base, exposing the latter for driving purposes.

4. A rocking slide construction comprising an outer metal base having an upstanding anchoring portion, a centrally apertured metal top plate having a base interlocking portion, said base and plate having an interlocking connection and forming a chamber, a headed anchoring member, the stem portion thereof being of less area than the plate aperture permitting relative rocking and axial movement therebetween, the headed portion being positioned in the chamber, resilient means carried by the top plate and through which the anchoring member extends, said means permitting head and base operative contact for slide mounting and normally separating the same when mounted, an outer molded base substantially enveloping the metal base, the shape of the latter being such that when molded into the outer base the two parts are permanently locked together, and a cushion member included within the top plate and the first mentioned base and having opposite faces engaging the plate and base and including a tubular aperture extending axially therethrough and of less cross-sectional area than the area of the anchoring member head.

5. A rocking slide construction comprising an outer metal base having an upstanding anchoring portion, a centrally apertured metal top plate having a base interlocking portion, said base and plate having an interlocking connection and forming a chamber, a headed anchoring member, the stem portion thereof being of less area than the plate aperture permitting relative rocking and axial movement therebetween, the headed portion being positioned in the chamber, resilient means carried by the top plate and through which the anchoring member extends, said means permitting head and base operative contact for slide mounting and normally separating the same when mounted, an outer molded base substantially enveloping the metal base, the shape of the latter being such that when molded into the outer base the two parts are permanently locked together, said outer base being of shatterable material and including an aperture in alignment with the plate aperture, said base aperture extending from its lower surface to the metal base, exposing the latter for driving purposes, and a cushion member included within the top plate and the first mentioned base and having opposite faces engaging the plate and base and including a tubular aperture extending axially therethrough and of less cross-sectional area than the area of the anchoring member head.

6. A rocking slide construction comprising an outer metal base having an upstanding anchoring portion, a centrally apertured metal top plate having a base interlocking portion, said base and plate having an interlocking connection and forming a chamber, a headed anchoring member, the stem

portion thereof being of less area than the plate aperture permitting relative rocking and axial movement therebetween, the headed portion being positioned in the chamber, and an outer molded base substantially enveloping the metal base, the shape of the latter being such that when molded into the outer base the two parts are permanently locked together, said outer base being of shatterable material and including an aperture in alignment with the plate aperture, said base aperture extending from its lower surface to the metal base, exposing the latter for driving purposes.

7. A rocking slide construction comprising an outer metal base having an upstanding anchoring portion, a centrally apertured metal top plate having a base interlocking portion, said base and plate having an interlocking connection and forming a chamber therein, a compressible cushion member within the chamber and normally under compression when the base and plate are interlocked, and a headed anchoring member, the stem portion thereof being of less area than the plate aperture permitting rocking and axial movement therebetween, the head portion being positioned in the chamber and laterally engaged by the cushion means for normally constraining the head anchoring member toward perpendicular position relative to the base and plate, said headed anchoring member being arranged to initially and operatively engage the chamber exposed portion of the base for slide mounting by pressure applied to the base exterior, said molded base including an exposed aperture in alignment with the plate aperture, said base aperture extending to the metal base for exposing same for slide drive mounting.

8. A rocking slide construction comprising an outer metal base having an upstanding anchoring portion, a centrally apertured metal top plate having a base interlocking portion, said base and plate having an interlocking connection and forming a chamber, a headed anchoring member, the stem portion thereof being of less area than the plate aperture permitting relative rocking and axial movement therebetween, the headed portion being positioned in the chamber, resilient means carried by the top plate and through which the member extends, said means permitting head and base operative contact for slide mounting and normally separating the same when mounted, and a cushion member included within the chamber and having opposite faces engaging the plate and base and including a tubular aperture extending axially therethrough and of less cross-sectional area than the anchoring member head, the base and plate interlocking connection being positionable above the included chamber to form a well adapted to nestingly receive said resilient means carried by the top plate for confining the said resilient means against lateral movement relative to said plate.

WILLIAM H. NOELTING.
